UNITED STATES PATENT OFFICE

158,634

AIRPLANE

Paul S. Baker, James M. Shoemaker, and I. Nevin Palley, Dallas, Tex., and William C. Schoolfield, Easton, Conn., assignors to United Aircraft Corporation, East Hartford, Conn., a corporation of Delaware

Application January 3, 1949, Serial No. 12

Term of patent 14 years

(Cl. D71—1)

To all whom it may concern:

Be it known that we, Paul S. Baker, a citizen of the United States of America, residing in the city of Dallas, in the county of Dallas and State of Texas, and whose post office address is 5545 Stonegate Drive, Dallas, Texas; and James M. Shoemaker, a citizen of the United States of America, residing in the city of Dallas, in the county of Dallas and State of Texas, and whose post office address is 1407 Engle Street, Dallas, Texas; and I. Nevin Palley, a citizen of the United States of America, residing in the city of Dallas, in the county of Dallas and State of Texas, and whose post office address is 2442 Anzio Drive, Dallas, Texas; and William C. Schoolfield, a citizen of the United States of America, residing in the town of Easton, in the county of Fairfield, and State of Connecticut, and whose post office address is P. O. Box 672, R. F. D. #1, Bridgeport, Connecticut, have invented a new, original, and ornamental Design for Airplane, of which the following is a specification, reference being had to the accompanying drawings, forming a part thereof.

Fig. 1 is a top plan view of an airplane, showing our new design.

Fig. 2 is a front elevational view.

Fig. 3 is a side elevational view.

Fig. 4 is a perspective view.

Fig. 5 is a bottom perspective view.

Fig. 6 is a bottom plan view.

We claim:

The ornamental design for an airplane, substantially as shown.

PAUL S. BAKER.
JAMES M. SHOEMAKER.
I. NEVIN PALLEY.
WILLIAM C. SCHOOLFIELD.
